UNITED STATES PATENT OFFICE.

THEODORE N. JONES, OF CRISMAN, COLORADO, ASSIGNOR OF ONE-HALF TO
PALMER C. LOVELEND, OF CRISMAN, COLORADO.

AUTOMATIC BUCKET-DUMPING APPARATUS.

SPECIFICATION forming part of Letters Patent No. 701,812, dated June 3, 1902.

Application filed July 15, 1901. Serial No. 68,451. (No model.)

To all whom it may concern:

Be it known that I, THEODORE N. JONES, a citizen of the United States of America, residing at Crisman, in the county of Boulder 5 and State of Colorado, have invented certain new and useful Improvements in Automatic Bucket-Dumping Apparatus; and I do declare the following to be a full, clear, and exact description of the invention, such as 10 will enable others skilled in the art to which it appertains to make and use the same, reference being had to the accompanying drawings, and to the characters of reference marked thereon, which form a part of this 15 specification.

My invention relates to improvements in automatic bucket-dumping apparatus, more especially intended for dumping ore-buckets after they are drawn from the mining-shaft. 20 My object is to provide an apparatus of this class which shall be comparatively simple in construction, economical in cost, reliable, durable, and thoroughly practicable in operation; and to these ends the invention 25 consists of the features, arrangements, and combinations hereinafter described and claimed, all of which will be fully understood by reference to the accompanying drawings, in which is illustrated an embodiment thereof.

30 In the drawings, Figure 1 is a side-elevation, partly in section, illustrating my improved bucket-dumping apparatus. Fig. 2 is a front elevation of the same. Fig. 3 is a perspective view of the hinged bucket holding 35 and dumping device. Fig. 4 is a section taken through the top of a mining-shaft, illustrating the bucket-guide located near the top of the shaft.

The same reference characters indicate the 40 same parts in all the views.

Let the numeral 5 designate a framework which may be of any suitable construction. Mounted on a shaft 6, located in the upper part of the framework, is a sheave or pulley 45 7, over which passes the wire rope or cable 8, one extremity of which is connected with the bucket 9, while the other extremity leads to the drum of the hoisting apparatus. (Not shown.) The frame 5 is constructed on one 50 side to form an inclined track 5^a, having downwardly-curved cross-bars 5^b, between

the two main side bars 5^d, forming a sort of cradle in which the bucket is adapted to slide as it is drawn up out of and let down into the shaft 10, which is provided with a bucket-guide 12, located near the top of the shaft and arranged to direct the bucket to the cradle or guide track 5^a of the frame. To the extremity of this track 5^a is hinged, as shown at 13, a dumping device 14, normally held in a position to harmonize with the position and inclination of the track by weights 15, attached to the opposite sides of said device. The device 14, as shown in the drawings, is rectangular in shape and provided with a central 65 bar 14^a and a bar 14^c on each side of the central bar. On these bars is slidably mounted a cross-head 16, provided with a hook 17. Between this cross-head and one end of the device 14 are located two coil-springs 18, 70 which surround the bars 14^c, respectively. These springs are so arranged that as the cross-head is moved upwardly the springs are stretched and placed under tension. Mounted on the frame in front of the dumping device 14 is a leaf-spring 19.

As the filled bucket is drawn up out of the shaft it first engages the guide 12 at the top of the shaft and passes thence to the inclined track 5^a, and as it is drawn upwardly it finally 80 reaches the dumping device 14. The upper edge of the bucket is then engaged by the hook 17, which being mounted on the spring-held cross-head forms a yielding stop for the bucket and prevents injury to the structure 85 which might result from the sudden stopping of the bucket during its upward movement.

As the bucket lands on the dumping device 14 it is engaged by the leaf-spring 19, 90 which, together with the gravity of the bucket as the cable is slackened, throws the bucket and dumping device downwardly to the dotted-line position in Fig. 1, the dumping device engaging a stop or ledge A, mounted on 95 the frame. The bucket has now assumed the inverted position and dumps into a car 20 or other receptacle, as may be desired, the ore being carried from the bucket to the car by a suitable chute B. During the bucket-dumping operation the bucket is held in position on the device 14 by the hook 17 of the

spring-held cross-head. Then as the cable pulls the bucket upwardly the dumping device is raised to its normal position by its weights 15. Then as the cable is slackened 5 the contraction of the springs 18 draws the bucket downwardly below the spring 19, whereby the latter is prevented from acting on the empty bucket. The latter then passes downwardly on the track 5^a and thence into 10 the shaft 10. A roller A, journaled in the frame at the lower extremity of the bucket-track, forms an antifrictional bearing for the cable when the device is in use.

Having thus described my invention, what 15 I claim is—

1. In a bucket-dumping apparatus, the combination with a suitable supporting-frame, and a pulley mounted thereon, of an inclined guide-track mounted on the frame, a dumping device hinged at the upper extremity of 20 said track and arranged to tip downwardly, a spring mounted on the frame, arranged to engage the bucket when mounted on the dumping device and adapted to coöperate 25 with the gravity of the bucket to perform the dumping function, means for normally holding the dumping device in position to coincide with the position of the track, and a bucket-holding attachment mounted on the 30 dumping device.

2. In a bucket-dumping apparatus, the combination with a suitable supporting-frame, and a sheave or pulley mounted on the upper portion thereof, of a bucket - guide track 35 mounted on the frame in line with the pulley, a hinged dumping device normally forming a continuation of the track, means mounted on the dumping device for engaging and stopping the bucket when the latter has 40 reached its limit of upward travel, said bucket-stop being arranged to support the bucket on the dumping device when the latter is tipped downwardly and the bucket inverted, and means mounted on the frame, arranged 45 to engage the bucket when mounted on the dumping device and adapted to coöperate with the gravity of the bucket to perform the dumping function.

3. In a bucket-dumping apparatus, the combination with a suitable frame, a pulley 50 mounted on the upper part of the frame, and arranged to be engaged by the bucket-cable, of an inclined track mounted on the frame, a hinged dumping device normally forming 55 a continuation of the bucket - guide track, and a spring-held bucket-retaining device mount-

ed on the dumping device, the arrangement being such that as the bucket is drawn up the inclined track, and landed on the dumping device and the cable slackened, the gravity 60 of the bucket tips the dumping device and throws the bucket to an inverted position.

4. In a bucket-dumping apparatus, the combination with a suitable supporting-frame located at the mouth of the shaft, a curved 65 bucket-guide located in the upper part of the shaft, to cause the bucket to move easily out of the shaft to the bucket-dumping apparatus, an inclined guide-track mounted on the frame in alinement with the shaft-guide, 70 a hinged or pivoted dumping device mounted on the frame in alinement with the bucket-guides, means for normally holding the dumping device in a position forming a continuation 75 of the guide-track, and a yieldingly-retained bucket-holding device mounted on the dumping device.

5. In a bucket-dumping apparatus, the combination with a suitable supporting-frame, of an inclined guide-track mounted thereon, a 80 hinged or pivoted device mounted on the frame in alinement with the guide-track, and a spring-retained hook mounted on the dumping device and adapted to engage the upper edge of the bucket and support the latter 85 when in the inverted position.

6. In a bucket-dumping apparatus, the combination with a suitable supporting-frame, of a bucket-guide track mounted on the frame, a hinged or pivoted dumping device mounted 90 on the frame in alinement with the bucket-guide track, a spring-held cross-head slidably mounted on the frame and provided with a hook adapted to engage the upper edge of the bucket as the latter is drawn upwardly 95 to engagement with the dumping device, whereby the springs of the cross-head are placed under tension, and a leaf - spring mounted on the frame, arranged to engage the bucket when landed on the dumping device, and arranged to coöperate with the gravity of the bucket to tip the dumping device downward, and weights applied to the dumping device and normally holding it in position to form a continuation of the bucket- 100 guide track.

In testimony whereof I affix my signature in presence of two witnesses.

THEODORE N. JONES.
